UNITED STATES PATENT OFFICE

ONEY HOLLYWOOD, OF HYATTVILLE, WYOMING

FUR STRETCHER

Application filed April 13, 1929. Serial No. 354,878.

The object of this, my present invention, is the provision of a pelt stretching frame that shall be of an extremely simple construction, cheaply manufactured and marketed and 5 easily operated and which is adjustable to positively engage and stretch pelts of various sized animals which are arranged thereon.

To the attainment of the foregoing the improvement resides in the construction, combination and operative association of parts hereinafter described and definitely claimed.

In the drawings:

Figure 1 is a plan view of the improvement.

Figure 2 is a side elevation thereof.

Figure 3 is a perspective view of the slide- 15 able hook for engaging with the nose and lip portion of the pelt.

Figure 4 is a similar view of one of the hooks for engaging with the belly or back portion of the pelt.

Figure 5 is a similar view of the hook em- 20 ployed for engaging with the hind leg part of the pelt.

In constructing my improvement I make 25 use of two substantially similar members in the nature of elongated plates or bars 1. Obviously the bars may be constructed of any desired or preferred material. The bars or plates 1 provide the side members of my im- 30 proved stretching frame and will be herein- after referred to as such.

The side members 1 have one of their ends curved inwardly, as at 2 and 3, respectively. The inner face of the curved end 3 is straight 35 while the face of the end 2 is curved outwardly, as at 4. There is fixed on the flat face of the end 2 a plate or bracket 5 through which passes a pivot 6 that also passes through the end 3. The central portion of the curved face 40 of the end 2 provides a fulcrum which contacts with the straight inner face of the end 3.

There is slidably associated with the flat face of the end 2 of one of the side members 1 a hook that comprises a rod 7 that has a central or handle portion 8 and an inner offset or hooked end 9. The outer straight end of the hook is designed to engage with the nose portion of a pelt which is arranged on the frame, and the offset portion or hook 9 is designed to engage with the lip portion of the pelt. Ob-

viously it is, of course, to be understood that the pelt is to be arranged over the frame.

The side members 1, at their juncture with their inturned ends 2 and 3 have fixed thereto the ends of the side members of an arcuate spring 10. The curved arms of the spring are connected by a straight portion 11 that has an opening therethrough and through this opening there is passed the threaded end of the operating rod 11 of the improvement. 55 The rod 11 has screwed on the threaded portion thereof a nut 12, which is arranged on the straight portion 11 of the curved spring arms and which is held from turning by contact with the inner faces of the said arms.

The side members 1, a suitable distance from the two-armed spring 10, have their inner faces notched, and at the juncture of the said notches the said side members are preferably reinforced by pivotally supported links 13.

To the outer or confronting edges of these links there are pivoted, as at 14, plates 15 which are normally arranged at an angle with respect to the sides 1. The inner or confronting ends of the plates 15 are rounded upon themselves to provide barrels for pintles 16 which pass through similar barrels in the ends of a short plate 17. The rod 11 passes through a central opening in the short plate 17 but the said rod has attached thereto bearing elements which may be in the nature of pins or washers 18 and 19 which contact with the opposite faces of the said plate 17.

The rod 11 passes through a block 19 that is centrally fixed on a transverse bar 20. The block 19, on its opposite faces has centrally connected thereto straps 21 and 22, each of the said straps having attached to its free end hooks 23 which are best disclosed by Figure 4 of the drawings. One of these hooks is designed to be inserted in the belly portion of the pelt and the other in the back of the pelt next to the tail thereof.

The bar 20 passes through openings in the side members 1. The side members are provided with apertures 24 designed to register with any one of a series of apertures 25 in the bar 20, and when the pelt is properly arranged upon the frame there is passed 95 100

through the apertures 24 and one of the apertures 25 a holding pin 26.

The sides 1, at the ends thereof provided with the openings through which the bar 20 passes, are formed with angularly arranged spaced apertures or openings 27 through any one of which there is designed to be passed a pin or lug 28 that also passes through the looped end 29 of a two-armed hook 30. The arms of the hook 30 are designed to engage with the leg portions of the pelt.

The outer end of the rod 11 is formed with a handle 31, and it will be apparent that by adjusting the handle the sides of the frame will be swung away or toward each other and likewise by adjusting the hooks so that the same will properly engage with the different portions of the pelt it will be apparent that the pelt can be stretched in an easy and thoroughly efficient manner by simply turning the handle 31 on the rod 11.

With my improvement pelts of various sizes may be easily and quickly stretched and the frame is held in stretching position until the pelt is to be removed therefrom.

The simplicity of the construction and the advantages will, it is thought, be apparent so that further detailed description will not be required.

30 What I claim is:—

1. A pelt stretcher comprising a pair of members, each having a tapered end, means for pivotally connecting together said ends, a shaft arranged between the members, means for causing longitudinal movement of the shaft when the same is turned, an arm pivoted to each member intermediate the ends of the member, a plate loosely arranged on the shaft and to which the other ends of the arms are pivoted, means whereby the plate will follow the longitudinal movement of the shaft so that the arms will operate to move the members toward or away from each other, means for attaching a pelt to the members, means for holding the members in adjusted position, such means comprising a cross bar and the free ends of the members having slots therein through which the ends of the cross bar pass and means for adjustably connecting the cross bar with said members.

2. A pelt stretcher comprising a pair of members, each member having a tapered end, means for pivotally connecting together the tapered ends of the members, one end part 55 having a rounded surface for engaging a flat surface on the other member to provide a fulcrum between the members, a U-shaped spring member having its limbs connected with the inner faces of the members adjacent 60 the tapered ends thereof, a shaft having a threaded portion passing through the bight of the spring member, a nut fastened to the bight and through which the shaft passes, the free ends of the members each having a slot 65 therein, a cross piece passing through the

slots, means for adjustably connecting the cross piece with the members, said cross piece having a hole therein through which the shaft passes, a plate on the shaft, projections on the shaft, one on each side of the plate, a pair of arms pivoted to the plate, means for hingedly connecting the plates with the members, a sliding member on the tapered end of one rod having parts thereon for engaging parts of the head of the pelt and hook members adjustably connected with the pivoted members for engaging rear portions of the pelt.

In testimony whereof I affix my signature.
